AIR COMPRESSION TYPE FLUSH TANKS

Edward L. Harrow, 5134 48th Ave. S., Seattle 18, Wash.

Filed Apr. 14, 1958, Ser. No. 728,198

3 Claims. (Cl. 4—26)

My invention relates to improvements in air compression type flush tanks for flushing toilet bowls.

An object of my invention is to provide a simple and highly efficient air compression type flush tank to be used instead of a conventional type float controlled flush tank in connection with a toilet bowl.

Another object is to provide a long air compression type flush tank of sufficient capacity for use with a toilet bowl and of a small enough cross sectional dimension so that it can be installed within and concealed by a wall of conventional construction.

Another object is to provide an air compression type flush tank which is quiet in operation and does away with much of the noise common to flush tanks of the form now in common use.

Another object is to provide an air compression type flush tank in which water is stored under the full pressure provided by the water supply system with which the tank is connected and which will deliver the stored water for flushing purposes at a fast rate and at a substantially reduced and fairly constant pressure thereby providing efficient flushing operation without objectionable noise.

Another object is to provide a flush tank having therein a plurality of spaced apart water discharge control plates adapted to control water pressure by restricting the downward movement of discharging water in the tank, said plates being attached to and assembled on a rod which extends substantially the full length of the tank and supports the plates in spaced apart relation in the tank, the assembly of the plates on the rod providing ease of installation and efficient support of the plates in the tank without necessitating welding or otherwise attaching the plates to the walls of the tank.

Other objects of this invention will be apparent from the following description and accompanying drawings.

Figure 1 is a vertical sectional view of an air compression type flush tank constructed in accordance with my invention showing the same installed within a wall and connected with a toilet bowl.

Fig. 2 is a fragmentary cross sectional view, on a larger scale than Fig. 1, taken substantially on broken line 2—2 of Fig. 1.

Fig. 3 is a detached view of an assembly of water discharge control plates on a rod showing the same apart from the tank.

Fig. 4 is a top plan view, with parts broken away, illustrative of a rod supported assembly of water discharge control plates of modified form.

Fig. 5 is a view similar to Fig. 4 illustrative of a rod supported assembly of water discharge control plates of still another modified form.

Like reference numerals refer to like parts throughout the several views.

This flush tank comprises a tube or pipe 10 of substantial length and of a diameter or cross sectional dimension capable of being installed in the space 11 of an ordinary wall between two spaced apart wall mem-

2

bers 12 and 13 with the tank resting on a suitable support 32. The tank 10 has a top end closure member 14 and a bottom end closure member 15. The top closure member 14 is preferably tightly welded to the top of the tank 10. The bottom closure member 15 can be similarly welded or it can be a threaded type closure member of detachable form, such as a cap or a plug. The welded top closure member provides a completely air tight tank top and this is important in making it possible to maintain an ample supply of air for expansion purposes in the upper end of the tank 10 over long periods of time. I find that when the closure member 14 is carefully welded to the top of the tank loss of air from the tank is substantially eliminated.

A plurality of vertically spaced apart partition type discharge control plates are provided in the tank 10 to control the pressure of water as it discharges from the tank. The number of plates can be varied but I have found that three properly spaced discharge control plates 16, 17 and 18 are sufficient for satisfactory operation. The plates 16, 17 and 18 of Figs. 1, 2, and 3 are provided respectively with perforations 19, 20 and 21 and preferably all of said plates are secured to and assembled on a rod 22 which rests on the tank bottom 15 and extends substantially to the tank top 14. Securing the plates 16, 17 and 18 to the rod 22 simplifies and reduces the cost of construction and assembly of this flush tank by making it unnecessary to weld the plates to the tank or crimp the tank to hold the plates or otherwise attach the plates to the walls of the tank. These plates can be modified in form, as hereinafter explained and shown in Figs. 4 and 5. However, I preferably make the plates 16, 17 and 18 shown in Figs. 1 to 3, and the similar plates shown in Fig. 5, of a diameter only slightly less than the internal diameter of the tank 10 so that the plates assembled on the rod can be readily pushed into the tank and will be supported against vibration by the walls of the tank, but will not allow much water to flow between the margins of the plates and the wall of the tank. The rate of flow of water downwardly past each plate 16, 17 and 18 is largely dependent on the flow area afforded by the perforations 19, 20 and 21 when the plates are thus sized to fit closely within the tank. The cylindrical part of tank 10 can be a piece of pipe of conventional form.

The plates used in my flush tank are constructed so that each successive plate, downwardly considered, offers less resistance to the downward flow of water past it than is offered by the plate next above it. In the construction shown in Figs. 1, 2 and 3 this is accomplished by making the plates 16, 17 and 18 of uniform size and fairly close fitting and by making the perforations 19, 20 and 21 in the respective plates 16, 17 and 18 equal in number but of successively increasing size, downwardly considered. Another way to accomplish this result is to provide a successively increasing number of flow perforations of equal size in the successive plates 16, 17 and 18.

Still another way to provide for an increasing flow area past successive plates, downwardly considered, is illustrated in Fig. 4 and comprises omitting all perforations and accurately sizing each of a plurality of spaced apart plates 16a, 17a and 18a on a rod 22a so that each succeeding plate, downwardly considered, is slightly smaller than the plate above it.

Also, as shown in Fig. 5, an increasing flow area past successive discharge control plates 16b, 17b and 18b, downwardly considered, can be obtained by providing marginal notches 23, 23a and 23b in the respective plates, the notches being of varying size or number.

A water inlet pipe 24 is communicatively connected

with the lower end portion of the tank 10. Also the lower end portion of the tank 10 is connected by an outlet conduit 25, self closing flush valve 26 and flushing conduit 27 with a toilet bowl 28. The self closing flush valve 26 has a handle 29 by which it can be opened. This valve 26 is commonly known as a "flushometer" valve and is readily obtainable on the market.

The flow area provided by conduits 25 and 27 and valve 26 is substantially larger than the inlet flow area provided by the conduit 24. I find that satisfactory operation is provided by using an inlet conduit 24 of about one fourth inch diameter and outlet conduit means 25, 26, 27 equal to about one inch diameter.

When the self closing flush valve 26 is in closed position water entering through conduit 24 at substantially any pressure ordinarily provided by water service pipes will rise in the tank 10 and compress air in a space 30 in the upper end of said tank until the air and water pressure in the tank equalize. Then when the flush valve 26 is opened the expansive pressure of the compressed air will force the water past the discharge control plates 16, 17 and 18 and provide an even flow of water at a fast rate but at a pressure substantially less than the maximum tank pressure to the bowl 28 for flushing purposes.

Usually water will enter the tank 10 at a pressure of not less than about forty pounds per square inch. The water inlet pipe 24 is of relatively small diameter and does not supply this water at a very fast rate. When the flush valve 26 is opened the water pressure in the lower end of the tank 10 will drop quickly to a predetermined minimum and will remain near that minimum until substantially all of the water is flushed out or the flush valve 26 closes. Some water entering through the inlet pipe 24 passes directly to the bowl 28 and helps in the flushing operation.

The pressure of the expanding air in the upper end of the tank 10 decreases as the level of the water is lowered, in flushing. Successive water discharge control plates, downwardly considered, each provide a greater area for the flow of water past them. Thus the resistance to the discharge of water decreases as the air pressure on the water decreases and the result is that the plates regulate and reduce water pressure in the lower end portion of the tank 10 and keep this pressure substantially constant during the flushing operation. I find that noise is minimized and satisfactory flushing operation is obtained if the major portion of the water is allowed to discharge from the tank 10 under a pressure of about eleven pounds per square inch. This pressure can be attained by the use of discharge control plates of the types hereinbefore disclosed.

The foregoing description and accompanying drawings clearly disclose preferred embodiments of my invention but it will be understood that changes may be made within the scope of the following claims.

I claim:

1. In flushing apparatus, a long upright tank of relatively small cross sectional area capable of being concealed in a wall of a building, said tank being closed at both ends providing an air tight air pressure chamber in the upper end and a water receptacle below said air pressure chamber; a plurality of vertically spaced apart transverse discharge control plates within said tank, each discharge control plate having slightly less water obstructing area than the plate next above it, each dis-

charge control plate retarding downward movement of the water in the tank and the water retarding action of each successive plate being less than the water retarding action of the plate next above it providing for a reduction of the water retarding action of the plates as the air pressure on the water in the tank decreases and for an approximately uniform discharge of the water from the tank at a pressure substantially below the initial pressure at which the water is maintained in the tank; water inlet means connected with said tank; and flush valve controlled water outlet means connected with the lower end portion of said tank.

2. In flushing apparatus, a long upright tank of relatively small cross sectional area capable of being concealed within a building wall, said tank being closed at both ends providing an air pressure chamber in its upper end and a water receptacle below said air pressure chamber; water pressure supply means connected with said tank; valve controlled water outlet flush means connected with the lower portion of said tank; and a plurality of vertically spaced apart transverse discharge control plates disposed within said tank, each discharge control plate having openings therein providing restricted flow areas for water to pass from one side to the other 15 of the plate, the openings in successive plates, downwardly considered, affording successively greater flow areas and said plates reducing the pressure of water discharging from the lower end portion of the tank.

3. In flushing apparatus, a long upright tank of relatively small cross sectional area capable of being concealed within a wall of a building, said tank being closed at both ends providing an air pressure chamber in its upper end and a water receptacle below said air pressure chamber; water pressure supply means connected with the lower end portion of said tank; water outlet means of greater flow capacity than said water pressure supply means connected with the lower end portion of said tank; a flush valve controlling the discharge of water through said water outlet means; a rod extending longitudinally within said tank substantially from end to end thereof; a plurality of spaced apart discharge control plates rigidly secured to said rod and the rod and plates constituting a one piece assembly, the plates being supported by said rod in vertically spaced apart relation in said tank, the marginal portions of said plates being disposed in close proximity to the walls of said tank minimizing water flow area between the plates and the walls of the tank; and flow passageways provided in each of said plates, the flow passageways in successive 20 plates, downwardly considered, being of successively increasing area, said plates reducing the pressure of the water at the location of said water outlet means.
